AUTOMATIC CONTROL FOR TIME
CONSTANT SYSTEMS

Alfred D. Bielek, Nutley, N. J.

Application July 27, 1949, Serial No. 107,050

2 Claims. (Cl. 178—44)

1

The present invention relates to an automatic control for time constant systems and more particularly to an automatically variable time constant filter.

Various devices have been proposed to improve the transmission of music, speech, etc., by reducing the audible distortion of sounds due to atmospheric disturbances and scratch noises, e. g. scratch noises of phonograph recordings. Generally, such devices deal with filtration means whereby all frequencies above or below an established cut-off are suppressed. The established cut-off, being effective within the audible frequency range, greatly reduces noises at, for example, the higher frequencies within the audible range, with, however, an accompanying suppression of other desirable sounds above the cut-off point. A manual control is usually provided to produce selective cut-off in the audible range. A control for such cut-off has heretofore usually been horizontal in performance in that the manual manipulation of the control means results in a series of sharp cut-offs, for example at selective frequencies, which, when illustrated graphically, indicate a horizontal performance of the cut-off control system along the audible frequency range.

According to my co-pending application Serial No. 63,321, now Patent No. 2,541,326, of which this is a continuation-in-part application, suppression of audible noise, instead of being controlled horizontally with a sharp cut-off at the cut-off frequency—thus eliminating harmonic content and musical timbre—is controlled vertically from a fixed but manually variable cut-off frequency point beyond which all higher frequencies are attenuated but not eliminated. Thus, the harmonic content is retained and the musical timbre is preserved while all audible noise and distortion are effectively suppressed. In the case of musical transcriptions and high quality shellac records, the apparatus reduces scratch noise to a negligible level so that it is extremely difficult to distinguish any surface noise or loss of high response at low amplitude levels even from a no-suppression condition, while loss of scratch and other noises are very pronounced.

However, my co-pending application refers to a fixed time constant of .22 second for a resistor-capacitor filter network in series with a variable gain control tube to filter a rectified A. C. signal from A. C. components so that the variable gain control tube operates entirely on a D. C. potential. The present application is an improvement on such time constant filter.

2

In automatic volume or noise control system energized by an A. C. current and utilizing D. C. control means, it is a usual practice to filter A. C. components in said D. C. control means by a resistor-capacitor network having an established time constant. The resistor-capacitor network always has a transmission delay time depending upon its time constant. The minimum time constant must be about .1 second long to provide adequate filtering of A. C. components and preferably about .25 second long. When a rectified signal level rises and falls slowly, e. g. the signal level as produced by symphonic music, the longer time constant is completely satisfactory because the D. C. output voltage can accurately follow the signal level, i. e. on a time vs. amplitude basis. However, when the signal level changes abruptly, as evidenced by pizzicato instruments or passages, where a single solo instrument is suddenly followed by a burst of music from a full symphony orchestra, the delay time of a long time constant filter makes it impossible for a variable gain control tube in series therewith to accurately follow the abrupt change in signal level. A time constant of short delay time will not remedy the situation because the "gate" action of the variable gain control tube becomes very noticeable and objectionable, and if short enough, will produce serious signal distortion. The resistor-capacitor network cannot have a delay time short enough to make the D. C. voltage follow the A. C. signal fast enough so that a rapid rise or decay of signal will essentially be instantaneously followed by the gate or control tube because of the presence of A. C. components which will produce serious signal distortion. Therefore, it follows that a filter of long time constant is satisfactory for slow music but not satisfactory for sudden "bursts" of music because the musical transient will not be properly reproduced and considerable "after swish" will be experienced by the action of the control or gate tube; and a filter of short time constant is unsatisfactory for the same condition because the gate action becomes too noticeable and abrupt—not being fast enough to be undetectable—and serious distortion takes place due to the presence of A. C. components in the D. C. control voltage.

These drawbacks can be remedied by an automatically variable time constant or automatically variable time delay so that the control tube will completely follow the signal under all conditions.

It is one object of the present invention to provide an automatically variable time constant filter. It is another object of the present inven-

50

55

tion to provide a variable delay time in a filter system for filtering A. C. components from rectified A. C. signals. It is a further object of the present invention to provide a variable time constant filter which will under all conditions of changing amplitudes allow a D. C. output voltage to completely follow an A. C. signal across a rectifier. Other objects and advantages of the present invention will become apparent from the description hereinafter following and the drawings forming part hereof, in which:

Fig. 1 illustrates a schematic diagram of a dynamic noise and scratch suppressor,

Fig. 2 illustrates a schematic diagram of an automatically variable time constant filter according to the present invention, and

Figs. 3 to 5 illustrate modifications of Fig. 2.

Referring to Fig. 1, an input signal is applied across the potentiometer 1, which is set to apply a fraction of the input voltage, e. g. $\frac{1}{10}$ of the input voltage, to the electronic amplifier 2. This amplifier may have a voltage gain of, for example, ten times the fractioned voltage applied to the amplifier. Where the potentiometer is set to apply $\frac{1}{10}$ of the input voltage to the amplifier and the amplifier has a voltage gain of ten, then the output voltage of the amplifier will equal the input voltage applied across the potentiometer, or will control the voltage in the apparatus at this stage to zero db gain. However, where the input voltage from one source may differ from that of another, the potentiometer may be re-set so that an amplifier with a voltage gain of ten can bring up a -20 db signal to zero db, which is the normal operating level. This control permits great flexibility of operation in regard to input and output voltages. A suitable resistance 3 is provided as a plate load for the amplifier 2, and the capacitor 4 together with a substantially high ohm resistor 5 comprise a high impedance output termination for the amplifier 2. The amplifier signal, e. g. a zero dbm signal, is transferred from the plate load 3 of the amplifier 2 through the capacitor 6 to the potentiometer 7, which is actually the control means for dynamic scratch noise suppression. The capacitors 6 and 8 and the potentiometer 7 are a frequency determining network which acts as a variable high-pass filter having a low frequency cut-off of about 2500 cycles when the arm of the potentiometer is at a maximum clockwise position. The characteristic of this network is such that amplitude increases with frequency so that essentially full amplitude is transmitted through the network from about 5000 cycles and upward. As the arm of the potentiometer is rotated counter-clockwise, the low frequency cut-off through the network increases gradually to about 6000 cycles, while maintaining the frequency pass characteristic above 10,000 cycles per second within -3 db of the maximum position amplitude level. Increasing counter-clockwise rotation beyond approximately 70% merely decreases the overall amplitude of the transmitted frequency band while only slightly altering the low-frequency cut-off point. The control, or potentiometer 7, may be manipulated so that a signal input of zero to maximum can be applied through the decoupling capacitor 9 to grid No. 1 of the amplifier 10. The amplifier 10 is a variable gain tube or a super-control variable gain amplifier essentially class A in operation with a maximum voltage gain of about ten with a low impedance load. It applies a high frequency feedback signal of varying amplitude through the capacitor 11 and the resistor 12, which are elements of a frequency

determining network of high-pass characteristics with a low frequency cut-off of about 2500 C. P. S., which, in conjunction with the network 6, 7 and 8, produces a fairly sharp cut-off characteristic at the lowest frequency point of the potentiometer 7. The feedback signal then goes to the cathode of the amplifier 2, forming a variable degenerative circuit which is most effective at the higher audio frequencies which fall within the scratch or noise distortion bands. The feedback signal is in phase with the A. C. voltage across a substantially low impedance 13 provided as the terminal of the cathode of the amplifier 2 in the feedback circuit. The switch 14 is an "on-off" switch positioned in the feedback voltage line. However, the switch may be positioned at any applicable position, preferably in the feedback circuit.

Simultaneously with the impression of voltage across the potentiometer 1 to the amplifier 2, a full input voltage is applied to the grid of the amplifier 15, which is an automatic frequency control voltage amplifier having a voltage gain of about 10, and the amplified voltage passes through the capacitor 16 to the potentiometer 17, the capacitor 16 and the potentiometer 17 forming a high-pass network to attenuate all frequencies below 1000 C. P. S. The band of passed frequencies is then applied to the grid of the amplifier 18, which, for example, may have a voltage gain of about forty-five. Potentiometer 17 is preset in an individual amplifier system so that an A. F. C. voltage of, for example, -40 volts may be developed across the capacitor 19 for peak amplitudes in the higher frequency region of average commercial records. This -40 volts potential is usually sufficient to cause complete cut-off of the amplifier 10. However, before the -40 volts potential reaches the capacitor 19, it is applied to the grid of said amplifier 18, having a grounded cathode and acting as an A. F. amplifier-diode detector, through the capacitor 20 and the diode rectifier 21, which causes a rectified D. C. voltage to be developed across the potentiometer 22, which is a variable potentiometer so that any potential from 0 to -40 volts A. F. C. voltage can be applied to the amplifier 10, and through the resistor 23 which, in conjunction with the capacitor 19, forms a high frequency filter network. The system 19, 22 and 23 is a frequency expansion control enabling a controllable cut-off characteristic for the amplifier 10 so that a zero to a fully open "gate" action can be obtained on peak passages.

Since the capacitors 16 and 20 and the potentiometers 17 and 22 attenuate all frequencies below 1000 C. P. S., no "gate" action in the amplifier will occur until sufficient high frequency components are present to mask undesirable noise or, for example, record scratch. The filter network 19 and 23 has a time constant of about .22 second.

I provide a divided network, illustrated by the resistors 24 and 25, so that only a fraction of the A. F. C. voltage is applied to grid No. 1 of the amplifier 10 through the resistor 26. The fraction of the dividing network 24 and 25 may be for example, a five to seven ratio of the A. F. C. voltage, which is a constant fraction, or it may be any other suitable fraction as long as it remains non-variable. Therefore, if the total A. F. C. controlled voltage is -10 volts, the voltage applied to grid No. 1 would be -7.1 volts. Since the ratio is constant, a linear rate of rise 75 of A. F. C. voltages would normally produce a

substantially straight line gate characteristic, but due to the saturation of amplifier 18, starting at about 25 volts with complete saturation at -40 volts, a modified logarithmic control of the feedback voltage to amplifier 2 is provided. When no signal is present, no A. F. C. voltage is developed and suppression is maximum according to the setting of potentiometer 7. As a signal is developed, for example from a record, low levels of music and scratch noise (even if of a comparatively high level) will produce only very slight opening of the "gate" of amplifier 10. As high content is increased, A. F. C. voltage increases at a linear rate to about 50% open "gate," and then, due to logarithmic scaling, the "gate" opens less rapidly.

The screen grid B+ potential of the gate control circuits is returned from the amplifier 10 through a decoupling filter formed by the capacitor 27 and resistor 28 and in conjunction with the load resistor 29 to the B+ potential bus 29a. Amplifier 15 is returned through the load resistance 32 to the B+ bus. The B+ bus is then returned to the B+ potential source through another decoupling filter formed by the capacitor 30 and resistor 31. The amplifier 18 circuit is returned through the load resistor 33 directly to the B+ potential source.

Therefore, according to the combination comprising the high frequency feedback system and the A. F. C. voltage control system hereinbefore described, it is apparent that I have provided an electrical feedback type dynamic noise and scratch suppressing apparatus whereby suppression is controlled vertically from a fixed but manually variable cut-off frequency point beyond which all higher frequencies are attenuated but not eliminated.

However, a filter system having a time constant of .22 second for the filter network 19 and 23, as hereinbefore mentioned, although being satisfactory generally for symphonic music, may be improved considerably by substituting for the network 19 and 23 an automatically variable delay instead of a fixed delay. According to Figure 1, the substitution of such an automatically controlled variable delay for the network 19 and 23 in a suppressor circuit is illustrated by the location AVTC (automatically variable time constant) shown with broken lines.

Figure 2 illustrates particularly the circuit of an automatically variable time constant system located at AVTC of Figure 1, which incorporates the variable resistor 22 and the usual or main filter network of fixed time constant 19 and 23 having a time constant of, for example, .22 second. The present invention comprises a novel modification of such fixed time constant filter which converts the fixed time constant into an automatically variable time constant. Basically, the modification comprises the addition of a plurality of amplifier-resistor-capacitor networks which function as auxiliary circuits and which "balance" each other depending upon the amplitude and duration of the signal across a rectifier.

Under static conditions, the resistor 34, which is in series with the resistor 22 and which is shunted by capacitor 35, provides a filter network which biases grid 1 of a thermionic tube 36, of substantially low plate resistance and in series with said filter network, at projected cut-off; therefore very little conduction takes place through the amplifier 36. The time constant of the resistor-capacitor network 34 and 35 is about

twice as long as the filter network consisting of resistor 23 and its load capacitor 19. Under conditions of slow rise of the unfiltered D. C. voltage at, for instance, point A, the D. C. potential at, for instance, points B and C, in the absence of circuit elements not heretofore described, will rise simultaneously. Point C is located at the input to the variable gain or "gate" tube 10. However, when an A. C. signal rises abruptly, the unfiltered D. C. voltage at point A will follow the A. C. signal instantaneously, but will lag appreciably at the output, or point C, due to the time constant of the network 19 and 23. Considerable time will elapse before the capacitor 35 will charge to the full value of the D. C. potential applied across it. If no signal was present at point A before the "burst," then the capacitor will be completely discharged and no bias will exist on grid 1 of the amplifier 36 and this amplifier will operate as a short circuit across the resistor 23 for as long a time as the capacitor 35 does not build up a charge sufficient to cut off the amplifier 36. Long before the amplifier 36 is cut off, the capacitor 19 will already have been charged up to the full instantaneous peak value of the D. C. voltage at point A. However, if a static D. C. potential exists at point C and is comparatively high, e. g. -20 volts, then the amplifier 36 will be cut off because the charge existing across the capacitor 35 would be at the projected cut-off for the tube 36. At such stage, a sudden rise in D. C. potential, e. g. to about -35 volts, the signal at point C would again lag because the voltage at point A is now more negative than before and the bias applied to grid 1 of the amplifier 36 is no longer sufficient to maintain the amplifier at projected cut-off and the amplifier conducts to charge the capacitor 19 to essentially the full value existing at point A, and shortly thereafter the capacitor 35 is charged to the full value existing at point A and a bias will again be applied to the amplifier 36 to place it at projected cut-off. If the signal has a high rate of repetition of pizzicato effects, the amplifier will successfully follow the fastest musical repetition so long as the value of capacitor 35 is not too large, e. g. the capacitor 35 should not have an excessively high value and should preferably have a value such that in combination with resistor 34, the time constant will be approximately twice that of the main filter network 19 and 23.

Since the amplifier 36 acts only to charge the capacitor 19, it provides, together with the resistor 34 and capacitor 35, a first auxiliary circuit and another or second auxiliary circuit is required to provide proper discharge characteristics to eliminate "after swish," or the excessive time lag in the discharge of capacitor 19. This is accomplished by providing, in combination with the aforementioned circuit, a secondary or second auxiliary circuit comprising a thermionic tube 37, which has a substantially low plate resistance, and which is connected so that its cathode is joined to a location in the voltage path of the aforementioned circuit between the resistor 23 and capacitor 19 through a biasing network consisting of capacitor 38 and its shunt resistor 39 and its grid 1 is joined to another location in the voltage path of said aforementioned circuit between resistor 34 and its shunt capacitor 35 through a resistance 40 and its load capacitor 41. The secondary circuit functions to automatically change the ordinarily fixed time constant of the filter network 19 and 23 to a variable discharge time constant so that any

variation in the signal amplitude is transmitted to the control tube or "gate" tube 10, according to the signal amplitude across the resistor 22 with the avoidance of "after-swish." For example, with a sudden decrease in signal at point A the voltage differential will change so that point A is positive with reference to point C. The biasing network consisting of resistor 40 and its load capacitor 41, which, in conjunction with the biasing network of resistor 39 and capacitor 38, normally keeps tube 37 at projected cut-off and has an extremely short time constant so that this voltage differential will act on the grid of tube 37 and the tube 37 will almost instantly conduct and discharge the capacitor 19 down to the value of D. C. voltage existing at point A. Thus the original "fixed" time constant of the network 19 and 23 is automatically reduced so that the signal existing at point A is almost instantly transmitted to the gate tube 10 and the gate tube will successfully follow rapid changes in the value of D. C. voltage at point A, such voltage changes as occasioned by pizzicato effects. However, in the case of a full symphony orchestra, it is desirable to have a slower decay characteristic when the music ends abruptly in order to preserve a high order of harmonics and timbre. For such purpose, the biasing network consisting of capacitor 38 and its shunt resistor 39 is such that as the tube 37 is discharging the voltage change across the capacitor 38 tends to increase, inducing a greater biasing voltage across the resistor 39 and tends to keep the tube 37 at or near projected cut-off, offering considerable opposition to the rapid discharge of the capacitor 19 to ground, due to the existence of a static charge plus an added dynamic charge built up across the network 38 and 39. When the average signal is low, only a very small static charge is built up across capacitor 38 and resistor 39. This, in conjunction with whatever dynamic D. C. charge is built up across the network, will produce only a negligible increase in decay time, even though musical transients may have a high peak value. When, however, a "loud" symphonic passage is sustained for any time, a considerable static D. C. biasing voltage is built up across capacitor 38 and resistor 39. This in conjunction with the dynamic decay voltage built up across capacitor 38 will offer considerable opposition to the flow of current discharging capacitor 39. This opposition is actually achieved by maintaining a higher bias on tube 37; substantially increasing its plate resistance temporarily over the normal "discharge" plate resistance. This action is essentially automatic and will quickly adjust itself to any signal conditions. The gradient of opposition, the time consumed before its initial application, and its duration are a function of the relative values of capacitor 38 and resistor 39. These values can be chosen to suit conditions. This opposition to the conduction of the charge on capacitor 19 to ground preserves the echo, as in the case of abrupt endings, and prevents interaction with the bias voltage developed across network 38 and 39, charging action of tube 36 and its associated elements of the capacitor 19 so that in the case of static conditions the tube 37 is kept from discharging on action of the tube 36 and increasing the charging time. Therefore, the network 38-39 actually causes instantaneous action in the case of percussion instruments and balances the action of the biasing network 40-41 so that slow action, or a longer time constant, is possible with regard to loud symphonic passages.

In the case of noise suppressors using extremely high suppression characteristics, additional elements may be added as shown by resistors 42 and 44, and capacitor 43 in Fig. 3. If noise reduction of the order of 35 db or so is attempted, the decay characteristics must be altered so that under dynamic signal conditions natural reproduction can be achieved. Resistor 42 and capacitor 43 serve to appreciably increase the decay time above that obtainable with the circuit of Fig. 2.

Depending on size of the resistor 42, a static charge will build up across the capacitor 43, since tube 37 is only at projected, not actual, cutoff, and a small leakage current will always flow to ground. This charge can be as high as $\frac{1}{3}$ of E_0 across capacitor 19. This static charge, in addition to the dynamic charge impressed across capacitor 43 as tube 37 conducts, will greatly delay the complete discharge of capacitor 19. The value of capacitor 43 determines the characteristic decay curve and time delay of the discharge of capacitor 19. Addition of resistor 44 as shown, depending on the relative values of resistor 42 and resistor 44, serves to further increase the static voltage across capacitor 43. A maximum voltage of about $\frac{1}{2}$ of the E_0 available across capacitor 19 can be so built up, effecting a very great delay to the final discharge, but not the initial part of the discharge curve of capacitor 19. However, if the total resistive value of resistor 42 and resistor 44 in series is equal to, or less than, the diode load resistance 22, the available peak D. C. voltage output will be reduced. The net effect of resistor 42, capacitor 43, and resistor 44, if values are properly chosen is to permit 35 or more db of noise reduction in very soft passages, but "pull up" the "floor" from which the suppressor "takes off" to about 20-25 db under usual signal conditions. Thus complete noise reduction and elimination can be achieved, while yet retaining the quality apparent only when using more moderate suppression.

Fig. 4 shows the addition of an anti-noise modulation device, composed of tube 45, capacitor 46 and resistor 47, as shown in effective parallel combination with capacitor 38 and resistor 39.

Repeated experiments have shown that a piano is the most difficult instrument to cleanly reproduce in a dynamic noise suppressor. The aforementioned AVTC circuits are generally swish-proof, but show a definite tendency to produce noise modulation under the influence of strong slowly to moderately repeated, notes, i. e. a sort of fuzzy sound after each single strong note in a piano rendition. This is due to the elements 38 and 39 slowing down the decay rate, normally in an entirely satisfactory manner, but somewhat objectionable for piano, to preserve timbre and echo, usually not present in noticeable degree in piano music. Tube 45 is usually kept at projected cutoff by capacitor 46 and resistor 47. This circuit shunts capacitor 38 and resistor 39, as shown. The time constant of capacitor 46 and resistor 47 are so chosen that most musical variations in level will not occur so rapidly that the bias on tube 45 will be overcome and cause it to conduct. In the case of piano music, the attack and decay of a single note are so rapid that, due to the relatively longer time constant, the instantaneous bias value will not be maintained high enough to keep tube 45 cut off. The net result is that it will conduct under the influence of a series of strong, single piano notes, effectively shorting out elements 38 and 39 and thus

maintaining a very fast decay time for the duration of the piano notes, giving effectively much cleaner reproduction without the usual accompanying noise modulation, otherwise noticeable in piano solos. If the piano notes are played at a highly repetitive rate, or are accompanied by an orchestra, tube 45 will be kept, for the most part, cut off, so that elements 38 and 39 will function in the usual manner.

Fig. 5 illustrates a modification of the invention in the provision of a driver-rectifier system delivering the potential to the input of the AVTC circuit. Element 48 is a driver tube developing sufficient A. C. voltage to drive the system to the required output. Tube 48 should have a low plate resistance if a high peak current output is desired (low mu triode). Transformer 49 couples the output of 48 to the rectifier 50, shown as a full-wave type. The primary impedance of 49 should match the plate resistance of 48 for maximum power transfer. The secondary may have any impedance or turns ratio desired, depending upon output voltage and available peak current desired. Capacitor 51 is the input "filter" condenser, used here to obtain peak output voltage to load resistor 52, which is preferably of fixed value.

In the RC coupled, shunt rectifier system of e. g. Fig. 1, the minimum charging time of capacitor 19 is limited by the current available at the output of the rectifier, which is exceedingly small, when RC coupled, resulting in a minimum charge time of several milliseconds. For certain applications, it may be desirable to greatly speed up the "charge" time to the order of a few microseconds. This is accomplished by using the circuit of Fig. 6. A low mu triode 48, coupled through transformer 49 (step-down turns ratio) to rectifier 50, which must have sufficient current capacity, so that peak charging currents of nearly any magnitude desired may be produced to make possible practically instantaneous charging of capacitor 19.

It is apparent, therefore, that the time constant of the combination of network herein described is actually variable and automatically controlled. Musical echo and timbre are faithfully preserved to the exclusion of practically every noise or swish which cannot be advantageously eliminated by any other way heretofore known.

What I claim is:

1. A system of time variable capacitance comprising a source of current, an output means, a main filter network electrically connected between said source and said output means and

consisting of a resistor and a shunt load capacitor of fixed time constant, a first auxiliary circuit comprising a first space discharge device having an anode, cathode and grid and a first biasing filter network connected across said cathode and grid and consisting of a resistor and a load capacitor therefor, said first biasing filter network being electrically connected between said source of current and said main filter resistor so that said first biasing resistor and said main filter resistor are in electrical series, said first space discharge anode being connected to said main filter network at a location in the current path between said main filter network resistor and said main filter network capacitor for charging said capacitor, a second auxiliary circuit comprising a space discharge device having an anode, cathode and grid and a second biasing filter network consisting of a resistor and a load capacitor therefor, said second biasing filter network being connected from the cathode of said second space discharge device to a location in the current path between said main filter network resistor and said main filter network capacitor and in shunt to said main filter network capacitor, said grid of the second auxiliary circuit space discharge device being electrically connected to a location in the current path between the resistor of said first biasing filter network and the said source of current, a third biasing filter network of short time constant consisting of a resistor and a load capacitor therefor and connected in said second auxiliary circuit between said source of current and the grid of said second auxiliary circuit space discharge device.

2. A system of time variable capacitance according to claim 1, comprising a fourth biasing filter network and a series resistor therefor, said fourth biasing filter network consisting of a resistor and its load capacitor, said fourth biasing filter network being connected from the anode of said second space discharge device to the said series resistor and said series resistor being connected to the current path between said main filter network resistor and said main filter network capacitor.
